(57) **CLAIM**

(22) Filed: **Aug. 17, 2012**

The ornamental design of a key pad for destination selection controller, as shown and described.

(30) **Foreign Application Priority Data**

DESCRIPTION

Feb. 17, 2012 (KR) 30-2012-0007266

FIG. 1 is a front perspective view of a key pad for destination selection controller showing our ornamental design;

(51) **LOC (10) Cl.** **10-05**

FIG. 2 is a front elevational view thereof;

(52) **U.S. Cl.**

FIG. 3 is a back elevational view thereof;

USPC **D10/108**

FIG. 4 is a left elevational view thereof;

(58) **Field of Classification Search**

FIG. 5 is a right elevational view thereof;

USPC D10/108; D21/812; 340/474; 200/520,
200/341; D13/158, 171, 174; 187/389-391,
187/396-397, 380, 390

FIG. 6 is a top plan view thereof;

See application file for complete search history.

FIG. 7 is a bottom plan view thereof;

(56) **References Cited**

FIG. 8 is front elevational view thereof, mounted to a pedestal;

U.S. PATENT DOCUMENTS

FIG. 9 is a right elevation view thereof, mounted to a pedestal;

D327,856 S * 7/1992 Loew et al. D10/106.95
D589,831 S * 4/2009 Friedli D10/108

and,

FIG. 10 is a back elevational view thereof mounted on a

pedestal.

The broken line representations in the figures, such as the pedestal, are for the purpose of illustration only, and form no part of the claimed invention.

pedestal.
